CLAIM

The ornamental design for a connector for a biomedical electrode, as shown and described.

DESCRIPTION

FIG. 1 is a top, left side, rear end perspective view of a connector for a biomedical electrode showing our new design;

FIG. 2 is a left side view of FIG. 1, the right side being a mirror image of FIG. 2;

FIG. 3 is a top view of FIG. 1;

FIG. 4 is a bottom view of FIG. 1;

FIG. 5 is a rear end view of FIG. 1; and,

FIG. 6 is a front end view of FIG. 1.
